UNITED STATES PATENT OFFICE

GIUSEPPE FOSSATI, OF MONZA, ITALY, ASSIGNOR TO FABBRICA ITALIANA MAGNETI MARELLI SOCIETA ANONIMA, OF MILAN, ITALY, A CORPORATION OF ITALY

IGNITION MAGNETO

Application filed July 30, 1930, Serial No. 471,821, and in Italy September 5, 1929.

The present invention has for its object a method for providing shoes for the inductor field in ignition magnetos.

This invention includes a method for connecting inductive permanent magnets with the field structure, and also concerns the inductor unit obtained by said methods.

In accordance with this invention the field shoes consist of a block or pile of superimposed iron sheets which are interconnected by means of rivets and by temporary connecting means, the said pile being located in a die in which the metal body or frame of the magneto is cast.

At the time of casting, the said field parts are thus embedded and positioned within the metal providing the said body or frame, and thereafter said temporary connecting means are removed through apertures of the magneto body or by machining.

Further in this invention the iron sheets providing the said pile comprise an intermediate portion which is identical for all the iron sheets, and on their sides these sheets have extensions which are offset in each pair of superimposed iron sheets.

Thus to the faces of the inductor field shoes opposite the magneto rotor a sufficient area for the flow of the total magnetic flux is imparted while their extensions engaging the permanent inductor magnets have a thickness which is reduced to the minimum permissible value.

Further in this invention inductor permanent magnets are used which are bar-shaped and have tapering heads which are shrunk in apertures of the said inductor parts.

On the annexed drawing is shown by way of example an embodiment of the present invention and

Figure 1 is a transverse section on line 1—1 of Fig. 5 of a magneto having an inductor unit according to this invention;

Figure 2 shows two superimposed sheets of the inductor in their respective superimposed position;

Figure 3 shows the sheet pile as assembled for location in a die for casting the magneto body in which it is to be embedded;

Figure 4 is a section on line 4—4 of Figure 3.

Figure 5 is a longitudinal section on line 5—5 of Fig. 1, with the magneto rotor removed.

Each sheet of the iron sheet pile intended to provide the inductor unit comprises a main rectangular portion 1 from which project extensions 2, 3 which are offset in the direction of the axis of the completed magneto. 60 To provide the pile, the subsequent sheets are located with their intermediate regions 1—1' superimposed and coincident with each other, while their extensions 2—3, 2'—3' are offset from each other, each sheet thus leaving a 65 free space in register with the extension 2—3 of the underlying and overlying sheets.

The several sheets 1, 1' . . . are arranged in a pile and are interconnected by means of rivets 4; then their extensions are bent into 70 the required shape as shown in Figure 3, and they are held in such shape by means of screw-threaded rods 5 having end nuts 6 and intermediate spacing sleeves 7.

A further transverse laminated pile 8 assembled by means of rivets 9 and strips 10 of non-magnetic material is fastened on pile 1, 1' by means of side lugs 8' engaged by rivets 11 fastened on a plate 12.

The unit shown in Fig. 3 is located in a die 80 in which the magneto body is to be cast, it being thus embedded in the metal mass of magneto body 18 (Fig. 1), which is formed, as usual, of aluminum.

After casting, the interconnecting rods 5 85 are removed, suitable bores being provided therefor in casting and the bores 15 of the magneto body and of the extensions 2, 3 are machined to their correct size, the sleeves 7 being thus destroyed. Then a bar shaped 90 magnet 13 having tapering heads 13' is inserted in each pair of aligned bores 15 and is driven or pressure-forced therein, said magnet being thus permanently engaged within the magneto body with its heads in intimate 95 connection with arms 2, 2' and 3, 3' embedded in said body and passed through by said bores 15 for providing a satisfactory flow of magnetic flux through said magnet and pole members 2, 2', 3, 3'. 100

Then the bore 17 for the rotor 14 is machined and thus the portions of the unit enclosed within the dotted circle in Fig. 3 are removed, the construction shown in Figure 1 being obtained.

5. As above stated each magnet includes an intermediate bar shaped portion 13 and two end heads 13'-13" having tapering shape and adapted to be shrunk within the bores 15 of the inductor unit.

10. Of course, the magnets 13 may have any desired profile or cross section, and they may be cylindrical or prismatical, it being essential only that they have tapering heads all 15 drawn on a single line, that is lying on the same conical or tapering surface.

Thus a good contact of the magnets with the field is secured without requiring screws or screwthreaded portions which are liable to become loose due to jolts and vibrations.

20. What I claim as my invention and desire to secure by United States Letters Patent is:—

1. A method for providing pole shoes in the field structure for ignition magneto, 25 consisting in providing a pile of superimposed sheets of magnetic metal, connecting them by connecting members, locating said pile in a die and casting therein the magneto body, and after casting removing the excess of said pile and said connecting members.

2. A method for providing pole shoes in the field structure for ignition magneto, 30 consisting in providing a pile of superimposed sheets of magnetic metal, connecting them by connecting members, locating said pile in a die and casting therein the magneto body, said pile extending across the body portion where a rotor seat is to be provided, 40 and after casting removing the excess of said pile and said connecting members.

3. A method for providing pole shoes in the field structure for ignition magneto, 45 consisting in providing a pile of superimposed sheets of magnetic metal each of said sheets including an intermediate portion coincident in all said sheets and extensions projecting from said intermediate portion and offset in superimposed pile sheets, connecting 50 them by connecting members, locating said pile in a die and casting therein the magneto body, and after casting removing the excess of said pile and said connecting members.

4. A method for providing pole shoes in the field structure for ignition magneto, 55 consisting in providing a main pile of superimposed sheets of magnetic metal, connecting them by connecting members, fastening a second pile of magnetic metal sheets on said 60 main pile, locating the assembled piles in a die and casting therein the magneto body, and after casting removing the excess of said piles and their connecting members.

65. A method for providing pole shoes in the field structure for ignition magneto,

consisting in providing a main pile of superimposed sheets of magnetic metal, each of said sheets including an intermediate portion coincident in all said sheets and extensions projecting from said intermediate portion 70 and offset in superimposed pile sheets, connecting them by connecting members, fastening a second pile of magnetic metal sheets on said main pile, locating the assembled piles in a die and casting therein the magneto body, 75 and after casting removing the excess of said piles and their connecting members.

6. A method for providing pole shoes in the field structure for ignition magneto, 80 consisting in providing a pile of superimposed sheets of magnetic metal, connecting them by connecting members, bending said pile to provide facing portions, locating said pile in a die and casting therein the magneto body, after casting removing the excess of 85 said pile and said connecting members, providing aligned tapering holes in said facing portions and forcing a tapering-headed bar-shaped permanent magnet in each pair of said aligned holes.

7. A method for providing pole shoes in the field structure for ignition magneto, 90 consisting in providing a pile of superimposed sheets of magnetic metal, each of said sheets including an intermediate portion coincident in all said sheets and extensions projecting from said intermediate portion and offset in superimposed pile sheets, connecting them by connecting members, bending said pile to provide facing portions, locating said pile in a die and casting therein the magneto body, after casting removing the excess of 95 said pile and said connecting members, providing aligned tapering holes in said facing portions and forcing a tapering-headed bar-shaped permanent magnet in each pair of said aligned holes.

8. A method for providing pole shoes in the field structure for ignition magneto, 100 consisting in providing a main pile of superimposed sheets of magnetic metal, connecting them by connecting members, bending said pile to provide facing portions, fastening a second pile of magnetic metal sheets on said main pile, locating the assembled piles in a 105 die and casting therein the magneto body, after casting removing the excess of said piles and their connecting members, providing aligned tapering holes in said facing portions and forcing a tapering-headed bar-shaped permanent magnet in each pair of said aligned holes.

9. In a magneto, an inductor unit comprising laminated blocks embedded in the magneto body, each of said blocks providing a pole face in the magneto rotor seat and having an extension, the extensions of said blocks being opposite to each other and provided with aligned tapering holes, and tapering-headed bar-shaped magnets each with 115 120 125 130

its tapering heads engaged in a pair of said aligned tapering holes.

being opposite to each other, and bar-shaped magnets each having its ends connected with said opposite extensions.

In testimony whereof I have signed my name to this specification.

GIUSEPPE FOSSATI.

10. In a magneto, an inductor unit comprising laminated blocks embedded in the magneto body each of said blocks providing a pole face in the magneto rotor seat and having an extension, the extensions of said blocks being opposite to each other and provided with aligned tapering holes, aligned 10 laminated blocks located intermediate said first named blocks and providing pole faces in said rotor seats, and tapering-headed bar-shaped magnets each with its tapering heads engaged in a pair of said aligned tapering

15 holes.

11. In a magneto, an inductor unit comprising blocks embedded in the magneto body each of said blocks providing a pole face in the magneto rotor seat and an extension 20 and consisting of superimposed and coincident sheets in register with said pole face and of staggered sheets in said extension, said extensions of said blocks being opposite to each other in pairs and having aligned 25 tapering holes, and tapering-headed bar-shaped magnets each with its tapering heads engaged in said aligned tapering holes of said opposite extensions.

12. In a magneto, an inductor unit comprising blocks embedded in the magneto body each of said blocks providing a pole face in the magneto rotor seat and an extension and consisting of superimposed and coincident sheets in register with said pole face and of 35 staggered sheets in said extension, said extensions of said blocks being opposite to each other in pairs and having aligned tapering holes, tapering-headed bar-shaped magnets each with its tapering heads engaged in said 40 aligned tapering holes of said opposite extensions, and aligned laminated blocks embedded in said magneto body intermediate said first named blocks and providing pole faces in said rotor seat.

45 13. In a magneto, an inductor unit comprising two blocks each formed of a stack of superimposed sheets of magnetic metal and embedded in the magneto body, each of said blocks comprising a main section which 50 provides a pole face in the magneto rotor seat and an extension of reduced thickness with respect to said main section, said extensions of said two blocks being opposite to each other, and bar-shaped magnets each 55 having its ends connected with said opposite extensions.

14. In a magneto, an inductor unit comprising two blocks each formed of a stack of superimposed sheets of magnetic metal 60 and embedded in the magneto body, each of said blocks comprising a main section which provides a pole face in the magneto rotor seat and an extension comprising only a portion of said sheets existing in said main 65 section, said extensions of said two blocks
